UNITED STATES PATENT OFFICE

95,146

DESIGN FOR A SHOE

Christy Reggie, Queens Village, N. Y., assignor to
J. M. Connell Shoe Co., South Braintree, Mass.,
a corporation of Massachusetts

Application July 25, 1934, Serial No. 52,684

Term of patent 7 years

To all whom it may concern:

Be it known that I, Christy Reggie, a citizen of the United States of America, residing at Queens Village, Long Island, in the county of Queens and State of New York, have invented a new, original, and ornamental Design for a Shoe, of which the following is a specification, reference being had to the accompanying drawing, forming part thereof.

In said drawing,

Fig. 1 is a side perspective view of a shoe showing my new design; and

Fig. 2 is a perspective view of the opposite side of the shoe shown in Fig. 1.

The cross lines of the drawing indicate the surface appearance of textile fabric as contrasted with the smooth texture of the leather portions which are unlined.

I claim:

The ornamental design for a shoe, substantially as shown and described.

In testimony whereof I affix my signature.

CHRISTY REGGIE.
